ALBERT F. HORLACHER, OF FREDONIA, NEW YORK

SELECTOR MECHANISM

Application filed May 7, 1927. Serial No. 189,650.

This invention relates to an electro-magnetic selector, which may be used for wire and wireless telegraphy, etc., the general object of the invention being to provide a magnet for operating ratchet mechanism to rotate a member which carries a brush which forms part of a commutator which makes and breaks the circuit of the magnet, with a plurality of keys for controlling the circuit of the 10 commutator in such a manner that by depressing a key, the device can be brought to rest at any desired point, with means on the rotary member for controlling a circuit of a receiving device.

15 This invention also consists in certain other features of construction and in the combination and arrangement of the several parts, to be hereinafter fully described, illustrated in the accompanying drawings and specifically 20 pointed out in the appended claims.

In describing my invention in detail, reference will be had to the accompanying drawings wherein like characters denote like or corresponding parts throughout the several 25 views, and in which:

Figure 1 is a diagrammatic view of one form of the invention.

Figure 2 is a detail view partly in section, showing one of the keys and the means for 30 controlling the circuit to the commutator thereby.

Figure 3 is a view similar to Figure 2 but showing the key depressed.

Figure 4 is an elevation showing a modified form of the invention.

Figure 5 is a plan view of this modification.

Figure 6 is a section on line 6—6 of Figure 5.

Figure 7 is a section on line 7—7 of Figure 5.

Figure 8 is a sectional detail view showing the ribbon carrying wheels and the commutator disk and their associated parts, of the modification.

Figure 9 is a diagrammatic view of the circuits of this modification.

Figure 10 is a view of one of the keys of said modification and its contact members.

Figure 11 is a diagrammatic view of a receiving device.

In the form of the invention shown in Figures 1, 2 and 3, 1 indicates a shaft supported for rotary movement and to which is fastened a brush arm 2 which is insulated from the shaft and which is adapted to move over a commutator disk 3 which is supported in a stationary manner adjacent the arm so that its contacts 4 will be engaged by the end of the arm during the rotation of said arm. The shaft also carries a ratchet disk 5 and an armature arm 6 is loosely mounted on the shaft and carries the pawl 6' for engaging the ratchet disk 5. A bracket 7 is supported in such a manner that the free end of the arm will work between the limbs of the bracket and the extent of movement of the arm is adjustable through means of the set screws 8 and 9 which are carried by the limbs of said bracket.

A magnet 10 is arranged below the arm and will pull the arm downwardly when the magnet is energized, against the action of a spring 11 which is connected with the arm and to a stationary part 12. A conductor 13 connects one end of the coil of the magnet with the screw 8 and a conductor 14 connects the other end of the coil with the brush arm 2. A conductor 15 connects the support 12 and the spring 11 with the negative terminal of a battery B. The positive terminal of the battery is connected by a conductor 16 with a brass plate 17 which is arranged in the casing 18 which carries a plurality of keys 19, each of which is held in raised position by a spring 20 arranged in the casing. Each spring 20 is connected by a conductor 21 with a contact 4 of the commutator. When in raised position, the springs 20 of each row of keys engage a brass strip 22 on the top of the casing, the strips 22 being electrically connected together by the conductors 22'. At each end of each row of keys or pushbuttons, is a brass spring 23 which is insulated from the brass plate 17 by the strip 24 of non-conducting material and each pair of springs 23 supports a strip 25 of non-conducting material, this strip 25 being so arranged that when a key or pushbutton is depressed, the end of

the spring 20 of said key will engage the strip 25 and then when the key is further depressed, the strip and the springs 23 connected with each strip 25 will be depressed until 5 the springs 23 engage the plate 17. Conductors 26 connect the springs 23 with the strip 22. Thus upon the depression of any key, the plate 17 will be electrically connected with all the strips 22 through means of the pair 10 of springs 23 which are depressed by the non-conducting strip 25 of that row of keys, one of which has been pushed downwardly and the conductor 26 which is connected with one of the strips 22, this strip 22 being connected 15 with the other strips 22 by the conductors 22'. It will, of course, be understood that the plate 17 extends under all the springs 23.

From the foregoing it will be seen that the circuit is broken by the springs 23 being out 20 of engagement with the plate 17, but when a key is depressed its spring 20 will move out of engagement with the bar 22 and into engagement with the insulated bar 25 and then further movement of the key will cause the 25 springs 23, which carry the bar 25, to engage the plate 17 which is connected with the battery. This will complete the circuit to the contacts of the commutator through plate 17, springs 23, conductor 26, strip 22, the springs 30 20 of the keys which are not depressed and conductors 21 of said keys. The circuit of the depressed key is broken, as its spring is resting against the insulated strip 25. The current will flow through the contact with 35 35 which the brush 2 is in engagement and then pass from the brush over conductor 14 through the magnet to conductor 13 and through screw 8, armature 6, spring 11, support 12 and conductor 15 to the battery. Thus 40 40 the magnet will be energized so that the armature is pulled downwardly thereby, which will cause the pawl 6' to move the ratchet disk 5 one tooth, which will cause the shaft to move with it. As the armature leaves the screw 8, 45 45 the circuit will be broken so that the spring 11 will pull the armature back against the screw 8, which will place the pawl 6' in engagement with the next tooth of the ratchet disk. Then the current will flow through the 50 50 next contact 4 to the magnet and thus the ratchet and the shaft will be moved another step. This step by step movement of the parts will continue until the brush 2 reaches the contact 4 which is connected with the spring 55 55 20 of the depressed key 19, when the parts will come to rest, due to the fact that the circuit is broken by the spring of the depressed key being out of engagement with the strip 22. Then the key can be released and as its spring 60 60 moves upwardly, the springs 23 will move off the plate 17 and thus break the circuits of all the keys. In this way, the shaft 1 can be moved to any desired extent by pushing upon the desired key.

65 A disk 27, carrying the contacts 28, is

fastened to the shaft, and a brush 29 engages the periphery of the disk, said disk and brush acting as means for controlling a circuit to a receiving device.

This selector could be used to send secret 70 messages either by wire or wireless telegraphy. A wheel, having on its periphery the letters of the alphabet, the numerals and punctuation marks, could be attached to the shaft 1, each movement of the ratchet causing 75 the letter wheel to move a space of one letter. On the shaft 1, a commutator, such as 27, would be attached, having the same number of contacts as the commutator 3. This second commutator is to be connected into 80 the line or radio transmitter in place of the key to make the breaks, one break corresponding to each time the letter wheel moves forwardly a distance of one letter. The receiving device would be practically the same, 85 but without the pushbuttons and the commutator 3. The letter wheels at the sending and receiving end would have to have the characters arranged in the same order and both would have to start from the same character. Blank spaces could be left on the letter 90 wheel to increase the deception.

In the modification, I provide means whereby the brush can be moved in either direction instead of in but one direction, as shown 95 in Figure 1. In this case, the shaft 1' carries a gear 5' and a pair of oppositely arranged pawls 30' and 31 are arranged to engage the gear. Each pawl is pivoted to a frame 32 which is pivoted to the shaft, one on one side 100 of the gear and the other on the other side thereof. Armatures 33 and 34 are pivoted to the shaft and extend in opposite directions and are arranged on opposite sides of the gear and each armature is connected with a 105 pawl by a link 35. Each armature works between the adjustable stops 36 carried by the frame so that the frame is tilted by the movement of the armature. The outer end of each armature also works between the adjustable 110 stops formed by the screws 37 carried by the bracket 13'. An insulated member 38 is fastened to the outer end of each armature and carries a conducting strip 39 which is adapted 115 to engage the end of the top screw 37 when the armature is raised. This conductor strip is connected with the spring 11' connected to a screw 40 carried by a bracket 41, said spring tending to hold the armature in raised position. The magnets for the armatures are shown at 42 and 43. The brush arm 2' carries a frame 44 in which is supported a shaft 45 on which is rotatably supported the brush wheel 46 and the drums 47, the said drums being formed of non-conducting material and having wound thereon the metal strips 48 and 49, one strip being wound in an opposite direction from the other and a spring 50 arranged in each drum tends 120 to hold the strip of said drum in wound up 125 130

condition thereon. These parts are so arranged that the wheel 46 will engage the contacts 4' on the commutator member 3', with the free end of the strip 48 fastened to contact member 1 which is formed of two parts and the free end of the strip 49 fastened to contact member 100 which is also formed in two parts. The free end of contact 1 is connected by a conductor 51 with a small magnet 52, while the free end of contact 100 is connected by a conductor 53 with a small magnet 54, these magnets controlling a spring switch arm 55 which is arranged in the main circuit of the device and is connected 10 with the brush arm 2' by the conductor 56. A contact 57 is arranged adjacent each of the magnets 52 and 54 for engagement by the switch arm 55 when the arm is attracted by the magnets, and each contact 57 is connected 15 with the brush arm 2' by the conductor 56. Each strip 39 is connected by a conductor 59 with each of the magnets 42 and 43 and these magnets are connected with the battery B' 25 by the conductors 60. Thus it will be seen that the switch 55 in its normal position will hold the main circuit of the device open and it will be necessary to energize either the magnet 52 or the magnet 54 to close said circuit. 30 The springs 20' of the keys 19' are normally in engagement with the brass bar 22' which is connected by the conductor 16' with the battery B'. A brass bar 61 is adapted to be engaged by the springs on the depression of 35 the keys and this bar 61 is connected by a conductor 62 to a battery B'' which is also connected with the magnets 54 and 52 by the conductors 63. Of course, the springs 20' are connected to the contacts 4' of the commutator by the conductors 21', as in the first form of the invention. A pair of insulated pins 64 and 65 is carried by the frame 44, the pin 64 acting to hold the strip 49 in engagement with the contact 4' in rear of the 40 contact which is engaged by the brush wheel 46, while the pin 65 holds the strip 48 in engagement with the contact 4' in front of the one upon which the wheel 46 rests so that neither the strip 48 or 49 is in engagement 45 with the contact 4' with which the brush wheel 46 is in engagement.

On the depression of a key or button 19', its spring 20' will move out of engagement with the bar 22', which is electrically connected with the battery B' and then said spring 20' moves into engagement with the bar 61 which is in electrical engagement with the battery B''. Thus current will flow from 50 said battery B'' through the bar 61, spring 20' of the key which has been depressed, conductor 21' to the contact 4' to which said conductor is connected. It will then pass over that strip 48 or 49 which happens to be in 55 engagement with said contact (say 49) to the

conductor 53 to magnet 54 and back to the battery over conductor 63. This will energize magnet 54 so that it will attract the switch arm 55 and as this arm engages the contact 57 of the magnet 54, it will close the main circuit of the device, as described in the first form of the invention. This main current will pass from battery B' to bar 22' over conductor 16' through the springs 20' of the keys which have not been depressed to conductor 21' to the contact 4' on which the brush wheel 46 rests and through said wheel and its arm to conductor 56 through switch arm 55, conductor 58, conductor strip 39 on armature 34 to magnet 43 over conductor 59 and back to the battery over conductor 60. As the armature 34 moves downwardly, it will strike the lower stop 36 on the frame 32, thus tilting the frame on the shaft and causing said frame, through the link 35, to move 70 the pawl 31 into engagement with the tooth of the gear 5' and thus move said gear one tooth. As the circuit is broken by the downward movement of the armature, the spring 11' will return the armature and on this return movement, the armature will strike the upper stop 36, thus throwing the frame upwardly and causing it to move the pawl 31 rearwardly to a point where it will rest over another tooth of the gear and thus be ready 80 to engage said tooth on the next downward movement of the armature. Thus the parts will be given a step by step movement, as before described.

When the brush wheel comes into engagement with the contact 4', the key of which is depressed, the circuit will be broken and the parts will come to rest. Then the key is released so that current will cease to flow through the magnet 54 and this will release 100 the switch 55 so that the parts are then all in inoperative position. If a key is depressed which would cause the current to flow through the strip 48, the magnet 52 would be energized to attract the switch 55 and then 105 current would pass through the magnet 42, which would cause the parts to move in a step by step manner in an opposite direction from that first described.

The only difference in this form of the invention over that first described, is that the shaft 1' and its attached parts can move in either direction according to the position of the brush wheel 46 and which key is depressed. 110

As will be seen, the strip 49 passes around the commutator in one direction from the frame 44 and the strip 48 passes around the commutator in an opposite direction, both strips being out of engagement with the contact on which the wheel 46 rests. Therefore, if a key is depressed which is connected with a contact in front of the wheel 46, the current will flow through the strip 48, but if a 120

key is depressed which is connected with a contact in rear of the wheel 46, the current will flow through the strip 49. In this form of the invention, the selector will work much quicker than in the first form.

5 The selector last described is based upon the same principle as that first described, that is, having the brush make and break the circuit until it rests upon a contact in the commutator, whose circuit to one terminal to the 10 battery is opened by a depressed pushbutton. The shaft 1' of this selector may be coupled to the shaft of a single control radio receiver and the receiver may be tuned by depressing the correct pushbutton, thus setting the tuning control at the division at which the desired station is heard. If a station is heard at a setting of 67° and it is desired to listen to one which is heard at a setting of 6° , it is 15 only necessary to depress pushbutton 6 and the selector will automatically reverse and come to rest at contact 6 of the commutator which corresponds to a setting of 6° of the tuning control. The following is a description 20 of the operation of this form of the invention:—

The contact wheel rests upon contact 95 of the contacts 4' and it is desired to revolve it to contact 89. Pushbutton #89 is depressed. 30 First the pushbutton spring breaks the circuit between contact 89 and the brass bar 22' which is connected to the negative terminal of the battery B'. As the spring 20' is further depressed, it makes a circuit between the negative terminal of the battery B'' and the contact #89, through the bar 61. Since the brush wheel 46 is on contact #95, the strip or ribbon 49 passes over all contacts from #1 to #95 and the strip or ribbon 48 passes over all 35 contacts from #100 to #95. Neither ribbon passes over contact 95. Ribbon 49 passes over contact 89 and is connected to one terminal of the magnet 54. The other terminal of magnet 54 is connected to the positive terminal 40 of the battery B''. Hence the magnet 54 will attract the iron switch lever 55. This makes a complete circuit through the reverse magnet 43 and the armature 34 will be attracted by the magnet 43. As the armature 45 descends, pawl 31 will be brought into mesh with the gear 5', the armature then strikes the stop 36 and moves the frame 32, thus moving the pawl 31 a distance of one tooth in the reverse direction (counter clockwise). The 50 lower stops 37 are insulated. The brush wheel will then be moved to the next contact, the spring 11' returning the armature to the contact 37 and the process will continue until the brush wheel 46 rests upon contact #89. 55 As the brush wheel 46 moves from contact 90 to contact 89, the ribbon 49 which has been winding up on the reel 47, will be wound up from contact #89, thereby breaking the circuit through the magnet 54 and releasing the 60 switch lever 55. The pushbutton is then re-

leased. The same operation takes place when it is desired to move the contact wheel in a clockwise direction, except that magnet 42 is connected to the circuit.

Since all contacts in the commutator in 70 clockwise direction from the brush wheel to 100 are connected to the ribbon 48, any pushbutton depressed between the contact wheel will make a circuit through the magnet 52 and close the circuit through the magnet 42, 75 thus making the gear travel in a clockwise direction, and since all contacts in the commutator in a counter-clockwise direction from the contact wheel to 1 are connected to the ribbon 49, any pushbutton depressed between 80 the one on which the contact wheel rests and 1 will make a circuit through the magnet 54 and close the circuit through the magnet 43, 85 making the gear travel in a counter-clockwise direction. When this unit is coupled to the shaft of a single control radio receiver, it will be necessary to place a gear 70 on shaft 1' one-half the size of a gear 71 on the shaft 72 of the radio receiver control in order to reduce the 360° movement of the selector to a 180° 90 movement of the radio control.

Figure 11 shows a form of receiving device which may be used with the invention. This receiver operates as follows:—

An incoming signal from parts 27 and 29 of 95 Figure 1, for instance, will energize the relay magnet 73 which will attract the armature 74 and close the circuit 75 through the magnets 76 at switch 77. Each impulse will advance the ratchet 78 a distance of 100 one tooth on disk 79. The solenoid magnets M^3 , M^4 , M^5 , M^6 , M^7 , M^8 , etc., one for each typewriter key, actuate the keys of the typewriter. A number of signals coming 105 at regular intervals will cause the contact arm 80 of commutator 81 to be connected to the solenoid actuating the desired key. When the rapid succession of incoming signals ceases, the circuit at 77 will be open and when the spring 82 lifts the armature 78' into contact with the spring 83, no current will flow 110 through the magnets 76 and the spring 82 will lift the armature 78' against the tension of the spring 82 into contact with screw 84, thus closing the circuit through the solenoid magnet which is connected to the contact arm 80 and the typewriter key will be depressed. This same selector may be used for controlling other devices, such as torpedos.

115 It is thought from the foregoing description that the advantages and novel features of my invention will be readily apparent.

I desire it to be understood that I may make changes in the construction and in the combination and arrangement of the several parts, 120 provided that such changes fall within the scope of the appended claims.

What I claim is:—

1. A selector device of the class described 125 comprising a shaft, a commutator having its 130

- arm connected with the shaft, magnetic means for giving the shaft a step by step rotation, a circuit for the magnetic means including the commutator and key operated means arranged in the circuit for controlling the extent of movement of the parts, such key operated means comprising a plurality of keys arranged in rows, a spring associated with each key, said means being connected with that part of the circuit which is connected with the commutator, a plate arranged under the keys and connected with the other part of the circuit, a plurality of springs insulated from the plate but contacting the plate when depressed, a conducting strip associated with each row of keys and normally engaged by the springs of the keys, means for electrically connecting the conducting strips together, means for electrically connecting one of the strips with the springs carried by the plate, strips of non-conducting material carried by the springs on the plate and engaged by the springs of the keys when a key is depressed whereby the plate will be electrically connected with the springs of the keys which are not depressed, while the spring of the depressed key will be out of electrical contact with the conducting strips and the plate.
- 30 2. A selector device of the class described comprising a shaft, a commutator operated thereby, magnetic means for giving the shaft a step by step movement in one direction, a second set of magnetic means for giving the shaft a step by step movement in the opposite direction, circuits including the commutator and the magnetic means, a switch for closing the circuits through either one of the magnetic means or the other, key operated means for closing the circuits of all the commutator contacts except that, the key of which is depressed and means associated with the commutator and operated by the key actuated means for moving the switch to close the circuit of one magnetic means or the other, such means including a pair of drums on the brush shaft of the commutator, a strip connected with each drum, said strips passing around the commutator in opposite directions, with one strip connected to one contact of the commutator and the other with the next contact, spring means for normally holding the drums with the strips wound thereon and means for holding the strips out of engagement with that contact which is engaged by the brush.

In testimony whereof I affix my signature.
ALBERT F. HORLACHER.
